UNITED STATES PATENT OFFICE.

HERMAN ROLLE, OF PHILADELPHIA, PENNSYLVANIA, ASSIGNOR OF ONE-HALF TO
H. S. ADAMS, OF PHILADELPHIA, PENNSYLVANIA.

INK-FOUNTAIN.

992,690.

Specification of Letters Patent. Patented May 16, 1911.

Application filed November 7, 1910. Serial No. 591,180.

To all whom it may concern:

Be it known that I, HERMAN ROLLE, a citizen of the United States, residing at 213 South Sixty-first street, Philadelphia, in the 5 county of Philadelphia and State of Pennsylvania, have invented certain new and useful Improvements in Ink-Fountains; and I do hereby declare the following to be a full, clear, and exact description of the invention, 10 such as will enable others skilled in the art to which it appertains to make and use the same, reference being had to the accompanying drawings, and to letters or figures of reference marked thereon, which form a part of 15 this specification.

This invention relates to improvements in ink fountains for printing presses, and more particularly job presses.

It has been found difficult to regulate the 20 supply of ink to the feed roll, and to conveniently clean the latter, owing to the fact that heretofore the bearings of the feed roll were stationary, or the bottom of the fountain was adjustable.

According to my invention, I arrange the 25 feed roll so that it may be swung on its bearings away from the mouth of the fountain, and also provide a detachable connection between the swinging frame carrying the 30 roller and an eccentric shaft, whereby when the roller is in normal position, and the connection is made, the space for the egress of the ink may be regulated.

Therefore, the object of the invention is 35 to provide means for regulating the supply of ink to the feed roller, and to provide means whereby the feed roller may be detached from the regulating means and thrown upwardly and away from the fountain for repairs or cleaning.

The invention also relates to the specific details of construction and arrangement of parts which will be hereinafter described, and particularly pointed out in the claims.

In the drawings: Figure 1 is a perspective 45 view of my improved fountain. Fig. 2 is a vertical central section of the same. Fig. 3 is a plan view. Fig. 4 is a side elevation, the detachable connection being disengaged and 50 the ink roll thrown up. Fig. 5 is a detail view of the eccentric shaft for adjusting the feed roller.

1 indicates a fountain, comprising an inclined bottom 2, and sides 2^a, each of which is curved at its forward end to form a seat 55 for the inking roll, when the latter is in operative position, and above the curved portions are perforations 4. An ink roll 5, is located in the forward end of the fountain, its shaft 6, being mounted in bearings in 60 depending arms 7, pivotally supported on screws 8, passing through the openings 4, in the sides 2^a.

On one end of the shaft 6, is rigidly secured a ratchet wheel 9, which is embraced 65 by the bifurcated arms 10, of an operating lever 11. Mounted in the operating lever is a spring pressed pawl 12, provided with a projection 13, with which a locking dog 14, may engage if it be desired to hold the 70 pawl out of operative position. By this construction, if it be found necessary to discontinue the feeding of ink from the fountain, the locking dog may be engaged with the pin which will hold the pawl out of contact with the ratchet wheel. It will of 75 course be understood that even though the pawl is disengaged from the ratchet wheel, the lever may continue to be operated by the usual connections (not shown). 80

The roll 5, is formed at its ends with flanges 17, to form a snug fit in the curved ends of the sides 2^a, which prevents the ink oozing out at the end of the fountain.

Each of the arms 7, is provided with a 85 pair of ears 18, and a pin 19, supported in said ears, to provide a means for coupling the detachable means, now to be described.

A shaft 20, is mounted in bearings in the rear of the sides 2^a, and under the bottom 2. 90 Near the ends of this shaft are eccentrics 21, which fit in openings 22, in detachable side bars 23, the latter having notches 24 at their forward ends to fit over the pins 19, and between the ears 18. Nuts and washers 25, 95 are fitted over the ends of the shaft 20, to hold the detachable bars 23 in position on the eccentrics. An adjusting lever 26, is secured to the shaft 20, near one end, and it is formed with a curved slot 27, through which 100 passes a screw 28, engaged by a binding nut 29, which binds the adjusting lever against the side of the fountain to hold the parts in set position.

In operation, the fountain is clamped to the press by the support and screw 30, and the roll 5, is thrown down on the pivots 8, to engage in the curved seats of the fountain. 5 Then the detachable connecting bars 23, are fitted between the ears 18 and the notches 24 engage over the pins 19. The adjusting lever 26, is now moved, forward or backward, as the case may be which turns the 10 shaft 20, hence by reason of the eccentrics 21, the roll 5, through the medium of the bars 23, is adjusted toward or from the forward end of the inclined bottom, and the ink 15 passage is regulated. This adjustment having been completed, the set screw 29, is screwed up against the lever 26, and holds the parts in position. Now if after operating the press for a while it be found that the ink flows too freely, or is sluggish, the 20 set screw 29 is released and the adjusting lever is turned accordingly, and the ink passage is regulated.

When desiring to clean the roll 5, the bars 23, are raised to disengage the notches 24, 25 from the pins 19, which frees the arms 7-7, and the latter may then be swung upwardly above the fountain 1, as shown in Fig. 4. When the roll is in this position, it may be 30 conveniently cleaned, and swung again in its operative position, and the connecting bar lowered, when the fountain is in condition for further operation.

A fountain constructed according to my invention is extremely simple, and will save 35 considerable time in cleaning the roll and affords a convenient means for regulating the flow of ink without stopping the press.

Having thus described my invention, what I claim is:

40 1. In an ink fountain, the combination with a stationary inclined bottom, a swinging frame pivotally supported at the end of the fountain, a roll mounted in the swinging frame, detachable elements engaging the 45 frame to hold the roll adjacent the end of the inclined bottom, means including a cam engaging the detachable elements for moving the latter toward or from the end of the fountain to position the roll with reference 50 to the end of the inclined bottom to regulate the passage of ink, and a handle for revolving the cam.

2. In combination, an ink fountain formed with curved end portions, a pivotally 55 mounted roll supported on the fountain and provided with end flanges which fit in the curved end portions, and means for adjusting the roll to regulate the passage of ink, said means including eccentrics and connecting bars.

3. In combination, an ink fountain comprising sides having curved ends and a bottom, a pair of hangers pivoted to the sides, a roll mounted in the hangers and fitting in 65 the curved portions of the sides, means for

intermittently moving the roll, eccentrics mounted on the fountain, bars connecting the eccentrics and the hangers, and an operating device for moving the eccentrics to adjust the position of the roll with reference 70 to the end of the bottom.

4. In combination, a fountain comprising sides and a bottom, a pair of hangers pivotally mounted on the fountain, a roll mounted in the hangers, a pair of detachable side 75 bars connected to the hangers, and means for moving the side bars toward or from the end of the fountain.

5. In combination, an ink fountain, a frame pivotally mounted in the upper part 80 of the fountain, a roll mounted in the frame below the pivotal points thereof, means for adjusting the frame, said means including an eccentric and a detachable connection between the eccentric and the frame, the detachable connection permitting of the frame 85 and roll being swung away from the end of the fountain.

6. In combination, an ink fountain, a pair of arms formed with ears and mounted on 90 the ink fountain, pins extending across the ears, a roll mounted in the arms, a shaft mounted on the fountain and having eccentrics, side bars formed with openings and notches, the eccentrics fitting in the openings and the notches engaging the pins, a 95 lever secured to the shaft, and means for holding the lever in adjusted position.

7. In combination, an ink fountain, a pair of arms formed with ears and mounted on 100 the ink fountain, pins extending across the ears, a roll mounted in the arms, a shaft mounted on the fountain and having eccentrics, side bars formed with openings and notches, the eccentrics fitting in the openings and the notches engaging the pins, a 105 lever secured to the shaft, said lever having an arcuate slot, a screw passing through the arcuate slot, and a nut engaging the screw to clamp the lever in adjusted position. 110

8. In combination, an ink fountain, a frame pivotally mounted on the fountain, a shaft and roll mounted in the frame, means between the fountain and the frame for adjusting the latter and the roll, said means 115 including a detachable device for disconnecting the frame to permit it to be swung upwardly and away from the end of the fountain, a ratchet wheel mounted on the shaft of the roll, a housing and lever mounted on 120 the shaft, a pawl pivoted in the housing and normally engaging the ratchet wheel, said pawl having a pin and dog pivoted to the housing and having a seat, said seat adapted to engage with the pin and hold the pivoted pawl out of engagement with the ratchet wheel.

9. In combination, a fountain comprising sides and an inclined bottom, a pair of hangers pivotally mounted on the fountain, a 130

roll mounted in the hangers, a revolving element mounted on the fountain, a detachable connection between the revolving element and the hangers, and a handle for turning the revolving element whereby to adjust the position of the roll at the end of the fountain.

In testimony whereof I have signed my name to this specification in the presence of two subscribing witnesses.

HERMAN ROLLE.
